ABSTRACT

A vice comprising a body part, a slide part movable relative to the body part 8 at least one jaw member pivotally mounted on the body part or the slide part so as to move angularly in a plane to accommodate a tapered article between the two jaws of the vice. Alternatively, there may be an adapter for fitting to a conventional vice and a jaw can be pivotally mounted to this adapter.

1
VICES

This invention relates to a vice and an assembly for a vice part.

The two vice jaws of a workbench vice are usually formed integrally with the body and slide respectively, the slide being the part movable relative to the body so that when an article to be worked upon is placed between the jaws and the slide is moved towards the body, the article can be gripped between the vice jaws. Although satisfactory for gripping most articles, conventional vices are not suitable for gripping a tapering article because only a small proportion of the surface area of the vice jaws contact the article. Apart from the possibility that the vice jaws may damage a tapering article, there is also the chance that the article may not be firmly secured between the vice jaws and may move while it is being worked upon.

The invention consists in a vice comprising a body part, a slide part movable relative to the body part and a jaw member adapted to be mounted on the body part and/or the slide part, the arrangement being such that the jaw member can move angularly in a plane.

The invention also consists in a vice comprising a first part, a second part movable relative to the first part, a jaw member adapted to be pivotally supported by the first part, an operating means for moving the two parts towards and away from each other.

One of the parts may have a convex surface and the jaw member has a corresponding concave surface so that the jaw member can pivot about the convex surface.

One of the parts may have a recess and the jaw member has a projection adapted to enter the recess when the jaw is mounted on the said one part, a portion of the jaw member and a portion of said one part being arranged to leave a gap therebetween or one of the said portions being deformable so as to enable the jaw member to pivot relative to the said one part.

There may be a second jaw member adapted to be pivotally mounted to the second part.

The invention also includes an assembly for a vice include an adaptor member adapted to fit onto a portion of a standard vice and a jaw member adapted to be pivotally supported by the adapter member.

Examples will now be described.

In the accompanying drawings:

FIG. 1 is a side view of a vice showing two examples of the invention with the left hand jaw in its fixed position.

FIG. 2 is a plan view.

FIG. 3 is a section in the direction of arrow III of FIG. 1 without the left hand member.

FIG. 4 is a rear view of the left hand jaw member.

FIG. 5 is a section on the line V—V of FIG. 4.

FIG. 6 is a sectional view in the direction of arrow VI of FIG. 1 without the right hand jaw member.

FIG. 7 is a rear view of the right hand jaw member.

FIG. 8 is a section along the line VIII—VIII of FIG. 7.

FIG. 9 is a scrap side view showing the left hand jaw member in its furthest downwardly adjusted position.

FIG. 10 is a sectional plan view of a part of the vice of FIG. 1 showing the right hand jaw in adjusted position.

FIG. 11 shows a mount for adding to existing vice to simulate left hand side of the vice of FIG. 1.

2

FIG. 12 shows a mount for adding to existing vice to simulate right hand side of the vice of FIG. 1.

In FIG. 1 there is a body 1 having a face 2 onto which a first example of the jaw member, namely jaw 3. A slide 4 is axially movable in body 1 and has a face 5 onto which a second example of the jaw member, namely jaw 6 can be fitted. The face 2 has a convex portion 7, an upper ridge 8 which extends across the lateral width of the face 5 and a lower ridge 9 which has a central projecting portion 10. The jaw member 3 has a main body portion 11 having a concave surface to fit convex portion 7, an upper rearwardly extending rim 12, a lower rearwardly extending rim 13 and two end portions 14 and 15 having two slots 16 and 17 respectively. The body portion 11 has a central recess 18 along the central part of its inner upper edge and this recess 18 must be at least as long as portion 10 and terminated at each end by a shoulder 18a.

When jaw member 3 is fitted onto face 2 of body 1, pins 19 extending transversely outward from one side of block 1 and another pin projecting out from the other side of block 1 engage the slots 16 and 17 to locate jaw 3 on block 1. If the jaw 3 is mounted with slot 17 on the pin 19 as shown in FIG. 9, the jaw 3 can pivot about pin 19 as shown, but if the jaw 3 is reversed so that slot 16 is located on pin 19 as shown in FIG. 1, then jaw 3 is not pivotal but fixed.

In FIG. 9, the jaw 3 has been pivoted about pin 19 into its most downwardly position where portion 10 is located in the recess 18 whereas, in FIG. 1, the jaw 3 has been reversed and portion 10 now abuts the edge face 20 (FIG. 4) of jaw 3 which edge face is free of contact in FIG. 9 and defines a cavity 21 with the face 2 of the body 1. In this manner, jaw 3 pivots in a vertical plane but can be fixed in the normal position.

FIG. 6 shows the face 5 of slide 4 which face has a recess 22, a recess 23 and an open-sided slot 24 of less depth than recess 23 and connecting recess 23 with the side edge of face 5. The jaw 6 has a projection 25, and a projection 26 and an outer projecting rim 27. There is also two chamfered recesses 28 which gradually deeper in the transverse direction towards that part of the rim 27.

In FIG. 10 the projections 25 and 26 are located in recesses 22 and 23 respectively, and a wedge-shaped article is held between the jaws 3 and 6 so that jaw 6 has pivoted to its furthest possible pivoted position in the horizontal plane and projection 25 has moved slightly out of recess 22 and chamfered recesses 28 abuts the bottom of slot 26. Of course by reversing projections 25 and 26 in slots 22 and 23, jaw 6 is then fixed movable to pivot jaw 8.

In FIGS. 11 and 12 are shown two adapters 30 and 31 adapted to fit onto the jaws of a conventional vice and provide faces 32 and 33 corresponding to faces 2 and 5 of the vice shown in FIG. 1 so that the two jaws 3 and 6 can then be fitted to the adapters 30 and 31 respectively to convert a conventional vice.

In FIG. 1 the slide 4 has a tightening or tommy bar 40 for rotating screw threaded rod 41 to move slide 4 relative to body 1. Body 1 has a bracket 42 carrying a screw threaded clamping member 43 which can clamp to a work bench. This bracket is connected to body 1 by two bolts 44 and it can be arranged to attach this bracket to flanges 45 of body 1 through apertures 46 if desired.

Clearly the projections on jaw 6 and corresponding recesses in face 5 could be spaced from each other vertically rather than horizontally so that jaw 6 would then pivot in a vertical plane. Similarly, pin 19 could rise vertically from block 1 so jaw 3 would pivot in a horizontal plane.

In operation, if the article to be clamped tapers vertically the jaw 3 is used with slot 16 engaging pin 19 and jaw 6 is used with projections 26 in recess 22 so that the relatively raised portion 29 between the two chamfered recesses 28 abuts a normal part 29a of face 5 and leaves no gap therebetween. Thus jaw 6 is not horizontally pivotal but jaw 3 is vertically pivotal and will accommodate to the tapered article as slide 4 moves towards body 1 to clamp the article. If the article is then taken out of the vice and turned through 90° so that it tapers horizontally then both jaws 3 and 6 are reversed to their other positions on the body 1 and slide 4 respectively, so that shoulder 18a abuts ridge 8 and recess 18 lies along side ridge 8 and face 20, abuts portion 10 so that jaw 3 is immovable whereas raised portion 29 is spaced from open-sided slot 24 to allow jaw 6 to pivot horizontally to accommodate the taper of the article, a slide 4 is moved towards body 1.

It will be appreciated that the chamfered recesses 28 could be substituted by deformable, for example, resilient material.

It is possible for the convex surface 2 and pin 19 to be provided on the rear face of the pivotable jaw member 3 and a corresponding concave surface and slots can be provided on the body 1.

Clearly, it is also possible for the recesses 22 and 23 to be provided on the rear face of the jaw member 6 and the projections 25, 26 to be provided on the slide 4.

I claim:

1. A vice, comprising:

a first vice part and a second vice part movable relative to said first vice part to clamp an object between said vice parts;

said first vice part including a first convexly curved surface; a first vice jaw member having an operative surface for engaging an object to be clamped

and having a second concavely curved surface; said first and said second curved surfaces are curved complementary to each other and are in engagement, thereby permitting relative pivoting of said first vice part and said first jaw member only about a first axis;

said first vice part having laterally extending pins formed thereon at the axis of said first convex surface and said first jaw member having end portions with slots formed therein for the reception of said pins;

said first jaw member being selectively positionable at either of a first orientation with respect to said first vice part and a second orientation that is inverted from said first orientation with respect to said first vice part;

abutment surfaces formed on said first vice part and on said first jaw member in locations thereon such that when said first jaw member is at said first orientation, said abutment surfaces abut to fixedly locate said first jaw member and said first vice part at a first position with respect to each other; and when said first jaw member is at said second orientation, said abutment surfaces do not abut, so that said first jaw member is able to pivot with respect to said first vice part into and out of its said first position;

a second vice jaw member connected to said second vice part by pivot means, which are adapted to permit relative pivoting of said second jaw member and said second vice part only about a second axis that is substantially perpendicular to said first axis;

said second vice part having recess and said second jaw member having a projection capable of being entered into said recess when said second jaw member is being connected to said second vice part, whereby said second jaw member is rendered angularly adjustable relative to said second vice part.

2. The vice of claim 1, wherein said first axis is horizontal and said second axis is vertical.
